CLAIM

The ornamental design for a combined fireman's hood and face mask, as shown and described.

DESCRIPTION

FIG. 1 is a front elevational view of a combined fireman's hood and face mask showing our new design; FIG. 2 is a rear elevational view thereof; FIG. 3 is a right side elevational view of FIG. 1, the left side being a mirror image thereof; and FIG. 4 is a top plan view thereof.
